UNITED STATES PATENT OFFICE

1,997,076

MINING MACHINE

Thomas E. Pray, Chicago, Ill., assignor to Goodman Manufacturing Company, Chicago, Ill., a corporation of Illinois

Application October 15, 1931, Serial No. 568,912

20 Claims. (Cl. 262—28)

This invention relates to improvements in mining machines of the truck mounted type capable of cutting a kerf adjacent the mine bottom in front of the track or at various elevations and planes with respect thereto including shearing cuts at either side of the machine, and has as its general objects to provide a new and improved machine of the class described constructed with a view towards ruggedness, compactness, adaptability and ease and simplicity of operation.

A prior application, Serial Number 157,005, filed December 15, 1926 by William T. McCullough and entitled Improvements in mining machines, which issued as Patent No. 1,891,917 on December 20, 1932, discloses a machine of the general type shown in my invention. My invention is, however, an improvement over that shown in the McCullough patent in that a new and improved means is provided for supporting the cutting element for cutting in the various desired angles and planes with respect to the mine bottom and a new and improved means is provided for feeding and positioning the cutting mechanism together with a new and improved safety feature to safeguard against breakage of the mining machine driving mechanism or actuating mechanism therefor.

Other more specific objects of my invention will appear from time to time as the following specification proceeds.

My invention may be more clearly understood with reference to the accompanying drawings wherein:

Figure 1 is a top plan view of the device of my invention showing the cutter bar in position to cut a kerf adjacent the mine bottom or at various elevations with respect thereto and showing various other cutting positions of the cutter bar by dotted lines;

Figure 2 is an enlarged partial longitudinal sectional view of the forward or cutting end of the device embodying my invention;

Figure 3 is an enlarged side elevation of the rearward portion of the device embodying my invention with parts broken away and in section to more clearly show the details thereof;

Figure 4 is an enlarged partial plan view of the device embodying my invention with the cutter bar positioned for making a shearing cut in the mine wall and with parts broken away and in section;

Figure 5 is an enlarged fragmentary plan view of the rearward portion of the device of my invention with parts broken away and in section;

Figure 6 is an enlarged fragmentary plan view

of the forward portion of the device of my invention showing other parts broken away and in section than are shown in Figures 2 and 4;

Figure 7 is an enlarged detail view of the forward portion of the device of my invention with certain parts broken away and in section;

Figure 8 is an enlarged sectional view taken on line 8—8 of Figure 6;

Figure 9 is an enlarged partial end elevation of the rearward portion of the cutting mechanism and means for supporting the same with parts broken away and in section;

Figure 10 is an enlarged detail fragmentary plan view of a portion of the rearward portion of the device embodying my invention;

Figure 11 is a sectional view taken substantially on line 11—11 of Figure 10; and

Figure 12 is a diagrammatic view of the wiring connections of the device of my invention.

Like numerals refer to like parts throughout the various figures.

Referring now in particular to the embodiment of my invention illustrated in the accompanying drawings, a truck 10 is provided which is supported on wheels 11 and axles 12. A turntable 13 is provided on the forward end of said truck and supports a cutting element indicated at 14 for limited movement with respect thereto about a transverse axis and for complete rotational movement about a longitudinal axis.

The cutting element indicated at 14 includes suitable actuating mechanism herein shown as an electric motor 15 adjacent its rearward end, a central portion 16 secured to the forward end of the motor 15 and extending forwardly therefrom and supported in a relatively long bearing member 17 in a manner which will hereinafter be more fully described, a cutter frame 18 extending forwardly from the bearing member 17 beyond the extremities of the truck 10 and a cutter head 19 supported by said cutter frame for movement towards and away from said cutter frame. The cutter head 19 is provided with a cutter bar 20 having a cutter chain 21 of an ordinary construction movable thereabout in a usual manner.

A motor 23 is provided on the truck rearwardly of the turntable 13 for operating said turntable and the feeding and truck driving mechanism. Said motor is provided with a motor pinion 24 which meshes with and drives a spur gear 25 keyed on a transversely extending sleeve 26 freely mounted on one end of a transverse shaft 27. A pinion 28 is freely mounted on the transverse shaft 27 adjacent its opposite end and meshes

with and drives a spur gear 29 on a shaft 30. The shaft 30 is provided with a sprocket 31, which sprocket is connected with the rearward truck wheels 11 for driving said truck wheels by means 5 of a suitable chain and sprocket drive indicated at 32. The forward and rearward truck wheels and axles may be connected together in a suitable manner well known to those familiar with the art; as, for instance, a chain and sprocket 10 drive not herein shown since it is no part of my invention.

The pinion 28 is adapted to be selectively connected with the transverse shaft 27 and said shaft is adapted to be driven at one speed by 15 the sleeve 26 and at another speed through a suitable gear train connected with said sleeve in a manner which will hereinafter be more fully described so the truck 10 may be driven about the mine by the motor 23 at either a low feed- 20 ing speed or high traveling speed. The method of driving the transverse shaft 27 at either a high or low speed, and the method of selectively connecting the pinion 28 with said transverse shaft is as follows:

25 A pinion 33 is on the inner end of the sleeve 26 and meshes with and drives a spur gear 35 on a transversely extending shaft 36. A pinion 37 is keyed on the transversely extending shaft 36 and meshes with and drives a spur gear 38 freely 30 mounted on the transverse shaft 27. A clutch collar 39 is feathered on the transverse shaft 27 between the inner end of the sleeve 26 and the spur gear 38. The clutch collar 39 has clutch jaws 40 on opposite sides thereof adapted to 35 mesh with clutch jaws 42 on the inner end of the sleeve 26 or clutch jaws 43 on the face of the spur gear 38 so the transverse shaft 27 may either be driven directly through the sleeve 26 or may be driven at a reduced speed through the pinion 33, spur gear 35, pinion 37 and spur gear 38.

The clutch collar 39 is shifted along the trans- 40 verse shaft 27 to engage the clutch jaws 40 with either the clutch jaws 42 or 43 and cause the transverse shaft 27 to be driven at either a high or low speed by means of a suitable system of 45 levers which includes a clutch fork 44 operated by a suitable hand lever 45 in a usual manner.

A clutch collar 47 is feathered on the trans- 50 verse shaft 27 and has suitable clutch jaws thereon adapted to engage suitable clutch jaws on the face of the pinion 28 for selectively driving said pinion and the truck from the transverse shaft 27.

Referring now in particular to the means for 55 driving the turntable 13 from the motor 23 at a plurality of speeds, a worm 48 is keyed on the transverse shaft 27 and meshes with and drives a worm gear 49 journaled on its hub within a frame member 50 which serves as a means for 60 enclosing said worm and worm gear.

A sleeve 51 is feathered within the hub of the worm gear 49. A clutch collar 52 is in turn keyed within the sleeve 51. The clutch collar 52 has jaws 53 extending upwardly therefrom 65 adapted to engage clutch jaws 54 depending from a member 55 keyed to the upper end of a vertical shaft 56 coaxial with the worm gear 49. The member 55 is journaled within the upper portion of the frame member 50, and the lower 70 end of the vertical shaft 56 is journaled within the truck 10.

A spur pinion 57 is keyed to the vertical shaft 56 adjacent its lower end and meshes with and drives a spur gear 59 journaled on a vertically 75 extending stud 60 supported in the truck frame

10. The spur gear 59 in turn meshes with teeth 61 cut on the outer periphery of the turntable 13 for driving said turntable. Thus the turntable 13 may be turned at a high speed equal to the speed of the sleeve 26 or at a lower speed at the speed of the spur gear 38. This provides a high speed for positioning the cutter bar 20 and a lower speed for feeding said cutter bar while cutting.

10 While the mining machine is ordinarily fed into the coal on the track wheels 11, additional feeding means are provided for feeding said mining machine where the cutting conditions are exceptionally bad which herein comprises a rope drum 62 keyed on a sleeve 63 freely mounted on the vertical shaft 56 and having its lower end abutting the upper face of the spur pinion 57. Clutch jaws 64 extend upwardly from the sleeve 63 and are adapted to be engaged by suitable clutch jaws depending from the sleeve 51 15 for driving the rope drum 62 at either a high or low speed when desired in an obvious manner.

15 Suitable locking means are provided to prevent turning of the turntable whenever the truck is being driven on its track wheels. Said means herein comprise a latch member 65 having a slot 66 therein. A bolt 67 is provided for supporting the latch member 65 for sliding movement with respect thereto. The bolt 67 passes through the slot 66 in the latch member 65 and through the upper portion of the frame member 50 so said latch member may be moved in said slot to engage the top portion of the clutch collar 52 and prevent engagement of the clutch jaws 53 with the clutch jaws 54.

20 Referring now in particular to the novel means for supporting the cutting element 14 for complete rotational movement about a longitudinal axis, as has been before mentioned, said cutting element is supported in the bearing member 17 25 disposed forwardly of the motor 15 and rearwardly of the cutter frame 18. Said bearing member is relatively long and is provided with a lower half 70 and a top half 71. The top and bottom halves are adapted to completely surround the central portion 16 of the cutting element 14 and are of substantially the same length as said central portion and are held together in a suitable manner well known to those familiar with the art; as, for instance, nuts and bolts. 30

35 Trunnion shafts 72 extend outwardly from opposite sides of the lower half 70 of the bearing member 17 and are journaled in trunnion supports 73 secured to the upper face of the turntable and extending forwardly therefrom at a 40 point adjacent the forward end of the truck when the cutting element is in a longitudinal position with respect to said truck. Thus the bearing member 17 and the entire cutting element may be tilted about the axis of the trunnion shafts 72 for adjusting the angle of the cutter bar with respect to the mine bottom to 45 compensate for a pitching seam or an uneven mine bottom.

50 With reference in particular to Figures 2, 4 and 6, it may be seen that the bearing member 17 is relatively long so as to provide a long bearing surface for the cutting element 14 and rigidly support said cutting element when cutting in a horizontal plane or planes inclined with respect to the horizontal. The central portion of the top and bottom halves of the bearing member 17 is recessed. An internal gear 74 is carried within this recessed portion adjacent the rearward end thereof and is adapted to be meshed 55

with a spur pinion 75 freely mounted on a longitudinally extending shaft 76 journaled within the cutting element 14 and adapted to be selectively connected to said shaft by means of a clutch collar 77 and clutch jaws 78 in a usual manner. Said longitudinally extending shaft is driven from the motor 15 in a manner which will hereinafter be more fully described for turning the entire cutting element 14 about a longitudinal axis within the bearing member 17 including the motor 15, cutter frame 18, and cutter bar 20.

Suitable means are provided for locking the cutting element 14 to the bearing member 17 during the cutting operation. Said means may be of any type well known to those familiar with the art but is herein preferably shown as being a pin 68 of enlarged diameter adapted to register with apertures 68a in the top half 71 of the bearing member 17 and the central portion 16 of the cutting element 14. The pin 68 is operated by a suitable hand lever 69 pivotally supported on the top half 71 of the bearing member 17 and locked in its various operative or inoperative positions by means of suitable locking means in a usual manner. With such an arrangement the cutter bar may be held in a steady position for cutting in planes inclined with respect to the horizontal as readily as cutting in horizontal planes along the ground or at various elevations with respect thereto.

Referring now to the means for supporting the rearward end of the cutting element 14 and moving said cutting element about the axis of the trunnion shafts 72, a boss 79 extends rearwardly from the rearward cover for the motor 15 adjacent the longitudinal central portion thereof. Said boss is journaled within a member 80 adapted to extend upwardly and rearwardly therefrom. The vertical portion of the member 80 is guided within a vertically extending guide formed within a portion 81 of a support member 83 fixed to the turntable 13 and extending rearwardly therefrom.

The means for tilting the cutter bar and moving the cutting element about the axis of the trunnion shafts 72 is supported on stud shafts 84 extending outwardly from opposite sides of a casing 85 for a worm gear 86 and worm 87 and journaled in the support member 83. Said worm gear is journaled within the casing 85 and has a threaded bore adapted to receive a threaded shaft 88 having its upper end pivoted to the rearwardly extending portion of the member 80. Said worm is driven by a shaft 89 by means of hand wheels 90 on opposite sides thereof so that rotation of either hand wheel 90 will rotate the worm gear 86 which will translationally move the threaded shaft 88 therethrough and which will in turn pivot the entire cutting element about the axis of the trunnion shafts 72 for adjusting the angle of the cutter bar 20 with respect to the mine bottom.

Referring now in particular to the cutter head 19 and cutter bar 20 and means for supporting said cutter head for movement towards and away from the cutter frame 18, a pair of parallel spaced guides 92 are provided on opposite sides of the cutter frame 18 adjacent the rearward end thereof. Said parallel spaced guides depend downwardly from the cutter frame 18 when the cutter bar 20 is disposed so as to cut a horizontal kerf adjacent the mine bottom and are adapted to be engaged by parallel spaced guides 93 extending upwardly from opposite sides of a support

member 94 for the cutter head 19. Each guide 92 is provided with a gib 95 extending forwardly therefrom and integral therewith and adapted to engage a corresponding recess in each parallel spaced guide 93. A portion of each parallel spaced guide 92 extends outwardly and around and abuts the side of each parallel spaced guide 93 and a retaining member 96 is secured to the forward face of each parallel spaced guide 92. Each retaining member 96 abuts the forward face of a parallel spaced guide 93 for supporting said guides for movement along the parallel spaced guides 92 towards and away from the cutter frame 18.

With reference to Figures 2, 6 and 7, it may be seen that the parallel spaced guides 92 and 93 are of a relatively heavy construction to adequately support the cutting element 14 and prevent spreading of said guides. Further, the gibs 95, which engage corresponding recesses in the parallel spaced guides 93, are provided to aid in guiding the parallel spaced guides 93 for movement along the parallel spaced guides 92 and to strengthen the parallel spaced guides 92 and aid in preventing the spreading of said guides.

A portion 97 extends forwardly from the support member 94 and provides a trunnion support for a member 98. A threaded shaft 99 is journaled within the member 98 and extends upwardly therefrom and is threaded within the hub of a worm gear 100 journaled within the cutter frame 18 of the cutting element 14. The lower end of the threaded shaft 99 extends through and below the member 98 and has a spur pinion 101 keyed thereto. A nut 102 is threaded on the lower end of said shaft and abuts the lower face of the spur pinion 101 for holding said pinion onto said shaft.

A portion of the threaded shaft 99 adjacent the top side of the member 98 is shouldered and abuts the top portion of the member 98 while the top face of the spur pinion 101 abuts the lower side of the member 98 so that rotation of the worm gear 100 will cause translational movement of the threaded shaft 99 with respect thereto which will move the support member 94 therewith along the parallel spaced guides 92 towards and away from the cutter frame 18.

The support member 94 has a cutter bar supporting member 103 journaled therein and depending therefrom. An annular ring 104 is secured to the top portion of the cutter bar supporting member 103 and abuts a shoulder 105 in the support member 94 for holding said cutter bar supporting member within the support member 94 and permitting said cutter bar supporting member to be turned within said support member.

The cutter bar supporting member 103 supports the cutter bar 20 in a usual manner well known to those skilled in the art and is provided with an arcuate shaped internal rack 106 secured to its top surface adjacent the forward end thereof. Said rack is adapted to be engaged by the spur pinion 101 on the lower end of the threaded shaft 99. Thus rotation of the threaded shaft 99 will cause pivotal movement of the cutter bar supporting member 103 within the support member 94 for positioning or arcuately feeding the cutter bar 20 along the coal face. It should be noted that the teeth of the pinion 101 and the rack 106 are curved to permit movement of the rack 106 by the pinion 101 during the cutting operation and to compensate for

weaving movement of the cutter bar 20 and support member 94 during the cutting operation.

Means are provided for locking the cutter bar supporting member 103 and cutter bar 20 in various fixed angular positions with respect to the support member 94 so the cutter bar may be positioned along one side of the track and fed into the coal while positioned to one side of the track in a position substantially parallel to the track for permitting a kerf to be cut in the coal along the mine bottom in front of the mine track. Said means may be of any type well known to those skilled in the art but herein comprises a pin 107 supported within the support member 94 for vertical movement with respect thereto and adapted to engage any one of a number of apertures 108 adjacent the outer edge of the annular ring 104 and cutter bar supporting member 103, which pin is operated by a suitable system of levers in an obvious manner.

Referring now in particular to the means for rotating the threaded shaft 99 and arcuately feeding or positioning the cutter bar 20, a clutch sleeve 109 is feathered to the threaded shaft 99 and has clutch jaws 110 depending therefrom and adapted to engage clutch jaws 111 extending upwardly from the worm gear 100. The clutch sleeve 109 is supported within a cylindrical portion of the cutter frame 18 for vertical movement with respect thereto and is vertically moved to engage the clutch jaws 110 with or disengage said clutch jaws from the clutch jaws 111 and selectively drive the threaded shaft 99 from the worm gear 100 by means of a suitable system of levers well known to those familiar with the art (not shown). Thus when the clutch jaws 110 engage the clutch jaws 111 and the worm gear 100 is being driven by the motor 15, rotation of the threaded shaft 99 is effected, and when the clutch jaws 110 are disengaged from the clutch jaws 111, said threaded shaft is translationally moved through the worm gear 100 for adjusting the position of the cutter bar 20 with respect to the mine bottom.

45 The worm gear 100 is driven by a worm 112 freely mounted on the forward end of the longitudinally extending shaft 76 and selectively connected to said shaft by means of a clutch collar 113 provided with clutch jaws 114 adapted to mesh with clutch jaws 115 integral with the worm 112 in a usual manner. Thus when the cutter bar 20 is positioned parallel with the mine bottom, said cutter bar may be arcuately moved by means of the spur pinion 101 and rack 106 50 for feeding said cutter bar across the face of the coal or positioning said cutter bar so it may be fed across the face of the coal below the mine rails by means of the turntable 13. When the cutter bar 20 is in a perpendicular position with 55 respect to the mine bottom on either side of the truck 10 as is shown by dotted lines in Figure 1, the spur pinion 101 may be used to arcuately move the cutter bar 20 in a vertical plane for feeding said cutter bar vertically with respect to the face of the coal for making a shearing cut in the mine wall.

Referring now in particular to the mechanism for driving the cutter chain 21 about the cutter bar 20 and actuating the feeding and positioning 60 mechanism for the cutting element 14 and cutter bar 20, the motor 15 is provided with an armature shaft 116 having an armature pinion 117 keyed to its forward end. Said armature pinion meshes with and drives a spur gear 118 keyed to the rearward end of a longitudinally extending shaft 119

5 journaled in suitable bearing supports within the central portion 16 of the cutting element 14. A bevel pinion 120 is keyed to the forward end of the longitudinally extending shaft 119 and meshes with and drives a bevel gear 121 journaled at opposite ends of its hub within the cutter frame 18 of the cutting element 14. The lower portion of the bore of the hub of the bevel gear 121 is splined and is adapted to be engaged by a splined shaft 123 slidably movable with respect thereto. Said splined shaft extends from the bevel gear 121 and is adapted to slidably engage the splined bore of a sleeve 124 journaled within the cutter bar supporting member 103 for driving said sleeve from the bevel gear 121. The sleeve 124 15 is secured within the cutter bar supporting member 103 in a usual manner and has a cutter chain sprocket 125 keyed thereto for driving the cutter chain 21 about the cutter bar 20.

20 The longitudinally extending shaft 76 is adapted to be driven from the motor 15 in reverse directions without reversal of the motor in the following manner:

25 A pair of bevel gears 127 is freely mounted on the longitudinally extending shaft 119. Said bevel gears face each other and mesh with a bevel gear 128 journaled on its hub within the central portion 16 of the cutting element. Suitable friction clutch mechanism is provided for driving either of said bevel gears from the longitudinally extending shaft 119 which may be of any type well known to those familiar with the art but which is herein shown as being friction clutches of the cone type. An internal cone 129 is integral with each bevel gear 127. External cones 130 are integral with opposite ends of a clutch collar 131 feathered on the longitudinally extending shaft 119 and each of these cones is adapted to engage an internal cone 129. The cones 130 are so arranged on the clutch collar 131 that only one bevel gear 127 may be driven at a time. It may thus be seen that when one cone 130 engages one internal cone 129 and one bevel gear 127 is driven from the longitudinally extending shaft 119 that the bevel gear 128 is rotated in one direction and that when the other bevel gear 127 is driven by the longitudinally extending shaft 119, the bevel gear 128 is rotated in an opposite direction.

30 A stub shaft 133 is keyed to the bevel gear 128 35 and has a worm 134 keyed thereto. The worm 134 meshes with and drives a worm gear 135 keyed to a longitudinally extending shaft 136. The worm 134 and worm gear 135 are of the self-locking type 40 so designed that the cutting element may be held in any desired position with respect to the turntable 13 until locked in a cutting position by external means which will hereinafter be more fully described. A spur gear 137 is keyed to the shaft 136 and meshes with and drives a spur gear 138 45 keyed to the longitudinally extending shaft 76 for driving said shaft.

50 It may now be seen that the entire cutting element may be reversely turned about a longitudinal axis by means of the motor 15 without reversal of said motor, for positioning the cutter bar to cut adjacent the mine bottom or the mine top, or to cut kerfs perpendicular to the mine bottom or at various angles with respect thereto, and that this turning speed is frictionally 55 controlled. It may also be seen that the cutter bar 20 may be pivotally moved about the axis of the splined shaft 123 by the motor 15 in opposite directions without reversal of said motor, and that said cutter bar may be moved towards 60

or away from the cutter frame 18 without reversal of said motor for adjusting said cutter bar to cut at various desired elevations with respect to the mine bottom, or for adjusting the position of said cutter bar with respect to the rib when cutting a shearing or vertical kerf in the mine wall and that these operations are effected through friction cone clutches hereinbefore described.

Referring now in particular to another of the novel features of my invention which includes a means to prevent overload of the cutting or feeding mechanism during the cutting operation, the cutting motor 15 is connected to the feeding motor 23 in such a manner that an overload on said cutting motor will cause said feeding motor to be disconnected from the line and thus prevent overload of the cutting mechanism and so that an overload on the feeding motor 23 while driving the feeding or traveling mechanism at either a high or low speed will cause said feeding motor to be disconnected from the line.

With reference to Figure 12, it may be seen that power is transmitted to the cutting and feeding motors by means of suitable conductors and an electric cable reel 139 which may be selectively driven from the transverse shaft 27 in a usual manner to wind an electrical conductor on or unwind an electrical conductor from said reel as the machine is traveling about the mine or being fed into the coal. A positive conductor 140 leads from the cable reel 139 to the cutting motor 15 and the feeding motor 23. A controller indicated at 143 is provided to start the cutting motor 15 by cutting out a resistance indicated at 144 in a usual manner. Another controller indicated at 145 is provided to cut out a resistance indicated at 146 in a usual manner to start the feeding motor 23. The controllers 143 and 145 are provided with blow-out coils 147 and 148, respectively, to prevent arcing between the controller contacts during the starting operation.

A conductor 149 leads from the negative side of the cutting motor 15 and controller 143 to the cable reel 139 and the negative side of the line. A conductor 150 leads from the controller 145 through a contactor 151, overload relay 152 and series resistance 153 to the conductor 149 and negative side of the line.

An overload relay 155 is provided to cut off current from a coil 156 for operating the contactor 151, the coil for operating the overload relay 155 being connected in series with the conductor 149 so that an overload on the cutting motor circuit will operate said relay.

A coil 157 is provided to open the overload relay 152 upon overload of the feeding motor 23. The overload relays 152 and 155 are normally closed and are only open upon overload of either the cutting or feeding motor circuits. When either of the relays 152 or 155 are open the circuit to the coil 156 for the contactor 151 is opened which opens said contactor and thus opens the circuit for the feeding motor 23 to stop said motor upon overload in either the cutting or feeding motor circuits.

Current is transmitted to the coil 157 for opening the overload relay 152 through the conductor 150 and contactor 151. The series resistance 153 is provided to effect opening of the overload relay 152 upon a certain predetermined overload of the feeding motor circuit. Another resistance 158 is shunted across the coil 156 and is adapted to be connected with said coil through a switch

indicated at 159 to effect opening of the overload relay 152 at a different predetermined overload than when directly connected through the series resistance 153.

The switch 159 has an operating handle 160 connected thereto, which handle is connected to the hand lever 45 for changing the feeding or traveling speeds from a high to a low speed by means of a crank lever 161 and a link 162. The crank lever 161 and link 162 are so arranged with respect to the operating handle 160 and hand lever 45 that when the clutch jaws 40 engage the clutch jaws 42 for operating the feeding or traveling mechanism at a high speed, the switch 159 is closed and the resistance 158 is shunted across the overload relay operating coil 156, and when the clutch jaws 40 engage the clutch jaws 43 for operating the feeding or traveling mechanism at a lower rate of speed, the shunt resistance 158 is disconnected from the overload relay operating coil 156.

It may now be seen that a higher resistance is provided for operating the overload relay 152 when the machine is traveling or feeding at a high rate of speed than when said machine is traveling or feeding at a lower rate of speed. The purpose in so arranging the resistances for the overload relay operating coil 156 is to so arrange said coil that the overload relay 152 will drop out at substantially the same load on the gear train when operating at a low rate of speed as at a high rate of speed. It may be seen that such an arrangement is very desirable and is an added safeguard to the feed gearing in that the reduction gears in the feeding or traveling gear train are under a greater load at a given load on the motor 23 when effecting feeding or traveling at a low speed than when effecting feeding or traveling at a high speed. Thus it is necessary that the overload relay 152 drop out at a lesser load on the motor 23 when the machine is being fed or is traveling at a low speed than at a higher speed.

It may thus be seen that during the traveling or cutting operation and upon overload of the feeding and traveling gearing that the overload relay 152 will open at the same load on said gearing while operating at either a high or low speed which will open the circuit to the coil 157 for the contactor 151 and open said contactor.

It may also be seen that during the cutting operation when the cutter bar 20 is being fed into the coal or across the face of the coal and said cutter bar hits an obstruction in the coal measure which causes an undue load on the cutting mechanism, that this load will be transmitted to the cutting motor 15 which will cause the overload relay 155 to open and which will cut out the feeding motor 23 from the circuit. This will stop feeding of the machine and allow the cutter bar 20 to free itself.

It may now be seen that new and improved means has been provided to stop feeding of the machine during overload of the cutting or traveling or feeding mechanism, and that this means is so arranged as to operate at substantially the same load on the feeding or traveling gear train while the machine is traveling or feeding at either a high or low rate of speed.

It may now be seen that a new and improved mining machine has been provided of a rugged, compact and accessible construction which is adapted to cut a kerf adjacent the mine top or bottom in front of the mine rails or at various intermediate positions and planes with respect thereto; that a new and improved means has

been provided for supporting the cutting mechanism for cutting in any desired angularly disposed plane with respect to the mine bottom which efficiently supports the cutting element so it may cut a kerf as efficiently in a vertical plane or plane inclined with respect to the vertical as in a horizontal plane; that a new and improved frictionally controlled gearing arrangement has been provided for positioning the cutter bar to cut the various desired kerfs and for feeding or moving said cutting element in reverse directions about a longitudinal axis or axis perpendicular with respect to the longitudinal without reversal of the driving motor therefor, and that a new and improved safety means has been provided to prevent overload of either the cutting or feeding mechanism and consequent breakage of either the cutting or feeding parts.

Although I have herein shown and described one embodiment of my invention, it will be understood that the construction and arrangement of the various parts may be altered without departing from the spirit and scope thereof. Furthermore, I do not wish to be construed as limiting myself to the specific form illustrated, excepting as it may be specifically limited in the appended claims.

I claim as my invention:

1. In a mining machine of the class described, a truck, a turntable on said truck, a cutting element including a motor, a cutter frame extending forwardly therefrom and beyond the forward extremities of said truck, a cutter head extending from said cutter frame and supported thereon for movement towards and away from said cutter frame, and means for supporting said cutting element on said truck for complete rotational movement about a longitudinal axis and pivotal movement about a transverse axis comprising a relatively long bearing member trunnioned on said turntable and surrounding and having bearing engagement with said cutter frame forwardly of said motor and rearwardly of said cutter head and a vertically movable member having bearing engagement with the rearward end of said motor adjacent the longitudinal central axis thereof.

2. In a mining machine of the class described, a truck, a cutting element including a motor, a cutter frame extending forwardly therefrom and beyond the forward extremities of said truck, a cutter head extending from said cutter frame and supported thereon for movement towards and away from said cutter frame, means for supporting said cutting element on said truck for complete rotational movement about a longitudinal axis and pivotal movement about a transverse axis comprising a relatively long bearing member trunnioned on said truck and surrounding and having bearing engagement with said cutter frame forwardly of said motor and rearwardly of said cutter head, and means for moving said cutting element about a transverse axis and holding said cutting element from lateral movement with respect to said truck comprising a vertically extending guide and a member having bearing engagement with the rearward end of said motor adjacent the longitudinal center line thereof and supported for vertical movement in said guide.

3. In a mining machine of the class described, a truck, a cutting element including a motor, a cutter frame extending forwardly therefrom and beyond the forward extremities of said truck, a cutter head extending from said cutter frame and supported thereon for movement towards and away from said cutter frame, means for sup-

porting said cutting element on said truck for complete rotational movement about a longitudinal axis comprising a relatively long bearing member supported on said truck and surrounding and having bearing engagement with said cutter frame forwardly of said motor and rearwardly of said cutter head, and means driven by said motor for rotating said cutting element within said bearing member comprising an internal gear fixed to the inner periphery of said bearing member and gear reduction means within said cutting element connecting said motor with said internal gear.

4. In a mining machine of the class described, a truck, a cutting element including a motor, a cutter frame extending forwardly therefrom and beyond the forward extremities of said truck, a cutter head extending from said cutter frame and supported thereon for movement towards and away from said cutter frame, means for supporting said cutting element on said truck for complete rotational movement about a longitudinal axis comprising a relatively long bearing member supported on said truck and surrounding and having bearing engagement with said cutter frame forwardly of said motor and rearwardly of said cutter head, and means driven by said motor for rotating said cutting element within said bearing member in reverse directions without reversal of said motor comprising an internal gear fixed to the inner periphery of said bearing member, and gear reduction means including reverse gearing supported in said cutting element and connecting said motor with said internal gear.

5. In a mining machine of the class described, a truck, a cutting element including a motor, a cutter frame extending forwardly therefrom and beyond the forward extremities of said truck, a cutter head extending from said cutter frame and supported thereon for movement towards and away from said cutter frame, means for supporting said cutting element on said truck for complete rotational movement about a longitudinal axis comprising a relatively long bearing member supported on said truck and surrounding and having bearing engagement with said cutter frame forwardly of said motor and rearwardly of said cutter head, and frictionally controlled means driven by said motor for rotating said cutting element within said bearing member in reverse directions without reversal of said motor comprising an internal gear fixed to the inner periphery of said bearing member, and gear reduction means supported within said cutting element including frictionally controlled reverse gearing for selectively connecting said motor with said internal gear.

6. In a mining machine of the class described, a truck, a cutting element including a motor, a cutter frame extending forwardly therefrom and beyond the forward extremities of said truck, a cutter head extending from said cutter frame and supported thereon for movement towards and away from said cutter frame, means for supporting said cutting element on said truck for complete rotational movement about a longitudinal axis comprising a relatively long bearing member supported on said truck and surrounding and having bearing engagement with said cutter frame forwardly of said motor and rearwardly of said cutter head, means driven by said motor for rotating said cutting element within said bearing member comprising a gear train including an internal gear fixed to the inner periphery of said bearing member, and means

for holding said cutting element in a fixed position with respect to said bearing member during the cutting operation.

7. In a mining machine of the class described, 5 a truck, a cutting element including a motor, a cutter frame extending forwardly therefrom and beyond the forward extremities of said truck, a cutter head extending from said cutter frame and supported thereon for movement towards 10 and away from said cutter frame, means for supporting said cutting element on said truck for complete rotational movement about a longitudinal axis comprising a relatively long bearing member supported on said truck and surrounding 15 and having bearing engagement with said cutter frame forwardly of said motor and rearwardly of said cutter head, means driven by said motor for rotating said cutting element within said bearing member in reverse directions without reversal of said motor comprising an internal gear fixed to the inner periphery of said bearing member and gear reduction means within said cutting element for connecting said motor with said internal gear including reverse gearing and 20 a worm and worm gear, and means for holding said cutting element in a fixed position with respect to said bearing member during the cutting operation.

8. In a mining machine of the class described, 30 a truck, a cutting element including a motor, a cutter frame extending forwardly therefrom and beyond the forward extremities of said truck, a cutter head extending from said cutter frame and supported thereon for movement towards 35 and away from said cutter frame, means for supporting said cutting element on said truck for complete rotational movement about a longitudinal axis comprising a relatively long bearing member supported on said truck and surrounding 40 and having bearing engagement with said cutter frame forwardly of said motor and rearwardly of said cutter head, frictionally controlled means driven by said motor for rotating said cutting element within said bearing member in reverse directions without reversal of said motor comprising an internal gear fixed to the 45 inner periphery of said bearing member and self-locking gear reduction means within said cutting element for selectively connecting said motor with said internal gear including frictionally controlled reverse gearing and a self-locking worm and worm gear, and means for holding said cutting element in a fixed position with respect to said bearing member during the cutting 50 operation comprising a pin and aperture lock.

9. In a mining machine of the class described, 55 a truck, a cutting element supported thereon including a motor, a cutter frame extending forwardly therefrom beyond the forward extremities of said truck, a cutter head movable towards and away from said cutter frame, and means for guiding said cutter head for movement towards and away from said cutter frame comprising a 60 pair of gibbed guides extending laterally from said cutter frame adjacent opposite sides thereof including grooved rearward faces, cooperating gibbed guides on said cutter head engageable with and slideable along said first mentioned gibbed guides including tongues engageable with 65 the grooves in said grooved rearward faces of said first-mentioned guides, portions extending along the sides of said first-mentioned guides, and a retaining member engaging the forward end of said first-mentioned guides for holding said first 70 and second mentioned gibbed guides in engage- 75

ment with each other and adjusting and supporting means interposed between said cutter head and cutter frame forwardly of said gibbed guides.

10. In a mining machine of the class described, 5 a track mounted truck, a turntable on said truck, a feeding motor, a cutting element including a motor, a cutter frame extending forwardly of said motor beyond the forward extremities of said truck, a cutter head supported by said cutter frame for movement towards and away from said cutter frame, said cutter head having a chain carrying cutter bar thereon mounted for movement about an axis perpendicular to the plane surface of said cutter bar, means for supporting said cutting element on 15 said turntable for complete rotational movement about a longitudinal axis comprising a bearing member supported on said turntable and surrounding and having bearing engagement with said cutter frame forwardly of said motor, means 20 connectible with said feeding motor for turning said turntable and feeding said cutter bar across the face in front of said truck or moving said truck longitudinally of the trackway for feeding said cutter bar into the coal face or longitudinally along the face of the coal, and means connectible with said second mentioned motor for driving said cutter chain, moving said cutter bar towards and away from said cutter frame and rotating said cutter frame about a longitudinal 30 axis comprising a longitudinally extending shaft having a geared connection with a cutter chain for driving said cutter chain about said cutter bar, and another shaft parallel with said first mentioned shaft and driven thereby by means of 35 a worm and worm gear.

11. In a mining machine of the class described, 40 a track mounted truck, a turntable on said truck, a feeding motor, a cutting element supported on said turntable including a motor, a cutter bar extending forwardly therefrom having a cutter chain movable thereabout and driven by said motor, means connectible with said feeding motor for turning said turntable and feeding said cutter bar across the face in front of 45 said truck or moving said truck longitudinally of the trackway for feeding said cutter bar into the coal face or longitudinally along the face of the coal, means operable independently of said cutter chain drive motor for disconnecting said feeding motor from its source of power supply on overload thereof, and other means operable independently of said means for disconnecting said feeding motor from its source of power supply for connecting said first and second mentioned 50 motors together so an overload on said cutter chain and said second mentioned motor will stop said feeding motor.

12. In a mining machine of the class described, 55 a track mounted truck, a turntable on said truck, a feeding motor, a cutting element supported on said turntable including a motor, a cutter bar extending forwardly therefrom having a cutter chain movable thereabout and driven by said motor, means connectible with said feeding motor 60 for turning said turntable and feeding said cutter bar across the face of the coal in front of said truck or moving said truck longitudinally of the trackway for feeding said cutter bar into the coal face or longitudinally along the face of the 65 coal, means operable independently of said cutting motor for disconnecting said feeding motor from its source of power supply on overload thereof, and other means operable independently of said means for disconnecting said feeding 70 motor.

motor from its source of current supply for connecting said first and second mentioned motors together so an overload on said cutter chain and said second mentioned motor will stop said feeding motor comprising an overload relay in said cutting motor circuit, a contactor in said feeding motor circuit and means for connecting said overload relay with said contactor so that overload of said cutting motor will open said relay which will cause said contactor to open and thus open said feeding motor circuit.

13. In a mining machine of the class described, a track mounted truck, a turntable on said truck, a cutting element mounted on said turntable including a projecting chain carrying cutter bar, a motor on said truck, means driven by said motor for driving said turntable at a plurality of predetermined speeds for feeding said cutter bar across the front of the truck or positioning said cutter bar in various positions with respect to said truck, means driven by said motor for moving said truck about the track at a plurality of speeds for feeding said cutter bar longitudinally along the track at a low speed or moving said truck at a higher speed, change speed gearing, an electrical circuit for operating said motor on said truck, an overload relay in said circuit, a resistance connected in series with said relay, another resistance shunted across the circuit of said relay, and means connected with said change speed gearing for cutting out said shunt resistance when operating at a low speed and connecting said shunt resistance in the circuit when operating at a high speed for equalizing the current through said overload relay and allowing said relay to operate upon overload of said change speed gearing independent of overload of said motor.

14. In a mining machine of the class described, a track mounted truck, a turntable on said truck, a cutting element mounted on said turntable including a cutter bar extending forwardly of said truck having a cutter chain movable thereabout and a motor for driving said cutter chain, a motor on said truck, means driven by said motor for driving said turntable at a plurality of predetermined speeds for feeding said cutter bar across the front of the truck or positioning said cutter bar in various positions with respect to said truck, means driven by said motor for moving said truck about the track at a plurality of speeds for feeding said cutter bar longitudinally along the track at a low speed or moving said truck at a higher speed, change speed gearing, an electrical circuit for operating said motor on said truck and said motor for driving said cutter chain, an overload relay having its operating coil connected in series with said feeding motor, a resistance connected in series with said relay, another resistance shunted across the circuit of said relay, means connected with said change speed gearing to cut out said shunt resistance when operating at a low speed and connect said shunt resistance in the circuit when operating at a high speed and equalize the current through said overload relay and allow said overload relay to operate upon overload of said change speed gearing independent of overload of said motor, another overload relay connected in series with said cutter chain driving motor, and means for connecting said relay with said feeding motor so the circuit to said feeding motor will be broken upon overload of said cutter chain and said cutter chain driving motor.

15. In a mining machine, feeding and cutting

mechanism therefor, change speed gearing for said mining machine whereby said mining machine may be fed at either a high or low speed, a motor for operating said feeding mechanism, an electric circuit for operating said feeding motor, and means whereby said feeding motor may automatically be disconnected from said electric circuit upon overload of said feeding mechanism irrespective of overload on said motor comprising overload circuit breaking means in said electric circuit, a resistance connected in series with said overload circuit breaking means, another resistance shunted across the circuit of said circuit breaking means, and means connected with said change speed gearing for cutting said shunt resistance out of said circuit when feeding at a low speed and cutting said shunt resistance into said circuit when feeding at a high speed.

16. In a mining machine, feeding and cutting mechanism therefor, change speed gearing for said mining machine whereby said mining machine may be fed at either a high or low speed, a motor for operating said feeding mechanism, an electric circuit for operating said feeding motor, and means whereby said feeding motor may automatically be disconnected from said electric circuit upon overload of said feeding mechanism irrespective of overload on said motor comprising overload circuit breaking means in said electric circuit, a resistance connected in series with said overload circuit breaking means, another resistance shunted across the circuit of said circuit breaking means, and means connected with said change speed gearing for cutting said shunt resistance out of said circuit when feeding at a low speed and cutting said shunt resistance into the circuit when feeding at a high speed comprising an electric switch and a connection from said switch to said change speed gearing.

17. In a mining machine, feeding and cutting mechanism therefor, change speed gearing for said mining machine whereby said mining machine may be fed at either a high or low speed including a gear shifting member, a motor for operating said feeding mechanism, an electric circuit for operating said feeding motor, and means whereby said feeding motor may automatically be disconnected from said electric circuit upon overload of said feeding mechanism irrespective of overload on said motor comprising overload circuit breaking means in said electric circuit, a resistance connected in series with said overload circuit breaking means, another resistance shunted across the circuit of said circuit breaking means, and a connection from said gear shifting member to said electric circuit for cutting said shunt resistance out of said circuit when said change speed gearing is connected to feed said mining machine at a low speed and cutting said shunt resistance into said circuit when said change speed gearing is connected to feed said mining machine at a high speed.

18. In a mining machine, feeding and cutting mechanism therefor, change speed gearing for said mining machine whereby said mining machine may be fed at either a high or low speed including a gear shifting member, a motor for operating said feeding mechanism, an electric circuit for operating said feeding motor, and means whereby said feeding motor may automatically be disconnected from said electric circuit upon overload of said feeding mechanism irrespective of overload on said motor comprising overload circuit breaking means in said electric circuit, a

resistance connected in series with said overload circuit breaking means, another resistance shunted across the circuit of said circuit breaking means, and means connected with said change speed gearing for cutting said shunt resistance out of said circuit when operating at a low speed and cutting said shunt resistance into the circuit when operating at a high speed comprising an electric switch and an operative connection from 5
10 said switch to said gear shifting member.

19. In a mining machine, feeding and cutting mechanism therefor, change speed gearing for said mining machine whereby said mining machine may be fed at either a high or low speed, 15
15 a motor for operating said feeding mechanism, another motor for operating said cutting mechanism, an electric circuit for operating said feeding and cutting motors, an overload relay having its operating coil connected in series with said feeding motor, a resistance connected in series with 20
20 said overload relay, another resistance shunted across the circuit of said overload relay, means connected with said change speed gearing for cutting out said shunt resistance when said feeding mechanism is operating at a low speed and connecting said shunt resistance in the circuit when said feeding mechanism is operating at a 25
25 high speed for equalizing the current through said overload relay and allowing said overload re-

lay to operate upon overload of said change speed gearing independent of overload of said motor, another overload relay connected in series with said motor for driving said cutting mechanism and an electrical connection from said relay to said feeding motor so the circuit for said feeding motor will be broken upon overload of said cutting mechanism and said cutting mechanism driving motor.

20. In a mining machine, a truck, a turntable on said truck, a cutting element on said turntable including a motor, a cutter frame secured to and extending forwardly of said motor beyond the forward extremities of said truck, a projecting chain carrying cutter bar carried by said cutter frame 15
15 for movement towards and away therefrom and for pivotal movement with respect thereto, and bearing means for supporting said entire cutting element including said motor for pivotal movement about an axis extending longitudinally thereof and about an axis extending transversely thereof for cutting in various angular planes with respect to the mine bottom comprising a bearing member trunnioned on said turntable and surrounding and having bearing engagement 20
20 with said cutting element rearwardly of said cutter head and forwardly of said motor.

THOMAS E. PRAY.
